Primary Examiner — Caron D Veynar*Assistant Examiner* — Laura Yu(74) *Attorney, Agent, or Firm* — Cantor Colburn LLP(57) **CLAIM**

The ornamental design for a drawer of washing machine, as shown and described.

DESCRIPTION

FIG. 1 is a front perspective view of a drawer of washing machine, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is another perspective view thereof;

FIG. 9 is an exploded perspective view thereof; and,

FIG. 10 is another perspective view thereof in an environment of use.
The broken lines are for environmental purposes only and form no part of the claimed design.

1 Claim, 8 Drawing Sheets(56)
